UNITED STATES PATENT OFFICE

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT

METHOD OF FORMING TELEPHONE PAY STATION BOXES

Application filed June 10, 1931. Serial No. 543,275.

My invention relates to the class of devices employed for collecting tolls for the use of telephone instruments, and an object of my invention, among others, is to provide a box 5 employed for this purpose which shall be composed of a single piece of sheet metal.

My improved process in the practice of which the objects herein set out, as well as others, may be attained is illustrated in the 10 accompanying drawing, in which—

Figure 1 is a view of a sheet metal blank from which my improved pay station box is formed.

Figure 2 is a view of said blank after a 15 preliminary step in the process.

Figure 3 is a view illustrating the formation of the blank shown in Figure 2.

Figure 4 is a view illustrating the shape of the box after an advanced step in the process. 20 Figure 5 is an end view of the box shown in Figure 4.

Figure 6 illustrates the step of forming the box to the shape shown in Figure 4.

Figure 7 illustrates the shape of the box at 25 a still further advanced step in the process.

Figures 8, 9, and 10 illustrate steps in the method of producing the box shown in Figure 7.

Figure 11 shows the shape of the box after 30 a still further advanced step in the process.

Figures 12 and 13 illustrate the method of shaping the box to the form shown in Figure 11.

Figure 14 is a view showing the shape of 35 the box in a still further advanced step in the process.

Figures 15 and 16 illustrate the method of producing the box of the shape shown in Figure 14.

40 Figure 17 is a perspective view of the completed box.

Telephone pay station boxes of the type shown herein have heretofore been made of two pieces of metal, one comprising the upper 45 part of the box and the other the lower part thereof, the lower member constituting about two-thirds of the box. Applicant has for a long time desired to make these boxes of a single piece of metal, and to this end many well-known concerns of high repute in the mak-

ing of dies and the formation of structures of all sorts from sheet metal have been requested to make the boxes in this manner. Many attempts have been made by such concerns to produce such boxes, but all such attempts 55 have invariably proved unsuccessful. After the failure of these various attempts, and after applicant had been informed by all of such manufacturers that such a box could not be produced, he set out in an attempt to 60 produce the structure. It was not, however, until after repeated trials resulting time and time again in failure, and after much perseverance, that applicant's attempts were 65 successful.

The process which applicant finally developed for the production of these one-piece boxes consists in forming at a preliminary step in the process a cup 11 on a flat sheet 10 of metal and before any attempt to impart a 70 box shape to the sheet. The formation of this cup may consume a number of steps, but I have shown only one and as illustrated in Figure 1 of the drawing wherein the cup is substantially of its final form, the final operation as to this cup being performed simply to correct distortion that may occur during subsequent steps in the formation of the box from the blank. 75

This initial formation of the cup 11 constitutes an important step in the process, and this is followed by an equally important step, the latter consisting in shaping the blank 10 with a tapered end 12 as shown in Figure 2, this tapered end being rounded at its outer 80 extremity and also rounded to meet the side edges of the blank. This shape is obtained preferably by means of dies thereby producing the blank 13 shown in Figure 2. In this step in the process not only are the corners reduced and rounded, but the opposite side edges of the blank are tapered from a wider dimension to a narrower dimension at the end 12. The blank at this step in the process is also provided with toothed projections 14 85 on that edge opposite the tapered end, and as shown in Figure 2, these toothed projections being an aid in the proper formation of the corners of the box at the bottom and open end thereof. At this step in the formation of the 90 130

blank the lower die 15 has a recess 16 to receive the cup 11, the upper die 17 having a hub 18 fitting into the cup 11, and as shown in Figure 3 of the drawing.

5 In a succeeding step in the process the lower die 19 has a recess to receive the cup 11 in the same manner as hereinbefore described, the upper die 20 being shaped to fit into said recess as shown in Figure 6. In this step 10 in the process the blank is given a box formation but open on one side and the bottom, and the cup 11 now has an important function in that it retains the blank accurately positioned between the dies and prevents any 15 crawling or creeping of the blank which crawling or creeping, if not restrained, would prevent an accurate formation of the blank. The blank 21 now appears with the top 22 closed and having a sloping front portion 23 and with sides 24 and an open bottom. A 20 rib 25 begins to appear around the bottom edge.

In another and subsequent step in the process, and as illustrated in Figures 7, 8, 9, and 23 10 the dies 26 and 27 are formed to more clearly define the general shape of the box to more closely approach its final form, the cup 11 in these operations performing its function of securely retaining the blank in 30 position to resist distortion of said blank.

In the operation illustrated by Figures 11, 12 and 13 the dies 28 and 29 operate upon the cup to correct its form and in the step illustrated in Figures 14, 15 and 16 the dies 33 30 and 31 operate upon the whole box structure to bring it more nearly to its final and correct shape, and as shown in Figure 17 wherein the completed structure is shown having the sides 24, the top 22 with its sloping forward portion 23 and the rib 25 extending around the two opposite sides and front, the bottom being open. The front 32 of the box has the cup 11 as hereinbefore described projecting inwardly within the 40 box near the top thereof.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to uses other than those above set 55 out.

I claim:

1. The process for forming an open back and bottomless box that consists in shaping a flat blank with a tapered and rounded end to 60 compose the top of the box, then stamping the blank to box form with an open back and bottom and before such forming creating a cup shaped projection in the blank to closely engage said cup shaped portion with a die 65 member to be held from lateral movement

thereby during said stamping operation, and subsequently, by a succession of operations, gradually perfecting the shape of the box and different portions thereon.

2. The process for forming an open back 70 and bottomless box that consists in shaping a flat blank with a tapered and rounded end to compose the top of the box, then stamping the blank to box form with an open back and bottom, and before such forming creating a 75 cup shaped projection in that part of the blank to compose the front of the box to closely engage said cup shaped portion with a die member to be held from lateral movement thereby during said stamping operation, shaping the top with a sloping front, and subsequently by a succession of operations, gradually perfecting the shape of the box.

3. The process for forming an open back 80 and bottomless box that consists in shaping a flat blank with a tapered and rounded end to compose the top of the box and the bottom edge with tooth shaped projections for formation of the corners between the sides and front of the box at the bottom thereof, then stamping the blank to box form with an open back and bottom, and before such forming creating a cup shaped projection in the blank to closely engage said cup shaped portion with a die member to be held from lateral movement thereby during said stamping operation, and subsequently, by a succession of operations, gradually perfecting the shape 90 of the box and different portions thereon.

4. The process for forming an open back and bottomless box that consists in shaping a flat blank with a cup shaped projection thereon, then placing the blank with the cup shaped portion closely engaged with and held by a die member, then stamping the blank to box form with an open back and bottom and creating a rib around the bottom edge, and then by a succession of operations, gradually perfecting the shape of the blank to form the 100 box and different portions thereof.

5. The process for forming an open back and bottomless box that consists in shaping a flat blank with a tapered and rounded end to compose the top of the box, then stamping the blank to box form with an open back and bottom, and before such forming creating a cup shaped projection in the blank which is closely engaged with a die member to hold it from lateral movement during said stamping, then forming a rib around the bottom edge of the structure, and then, by a succession of operations, gradually finally perfecting the shape of the box and the different portions thereon.

GEORGE A. LONG.
